LINER FOR TYPE SLUG CASTING MACHINES

Johan Walfrid Hemlin, Stockholm, and Carl
Arvid Andersson, Sundsvall, SwedenApplication July 3, 1934, Serial No. 733,550
In Germany July 17, 1933

4 Claims. (Cl. 199—58)

Our present invention relates to type slug casting machines and more particularly to means for adjusting the length of the type line in such machines.

5 The principal object of our invention is to provide an improved movable liner for use in combination with a mold for a type slug casting machine and to eliminate the drawback of liners hitherto used which resides in the necessity of 10 removing the cap of the mold every time it is desired to vary the length of the line, a procedure which, of course, is cumbersome and time-wasting.

Another object of our invention is to provide 15 a tool to be used in combination with our new movable liner to facilitate the correct adjustment of the liner.

With these and other objects in view our improved liner which is in known manner reciprocable in the longitudinal direction of the slot 20 of the mold is adapted to be held in position by frictional engagement with the opposed sides of the slot, said frictional engagement being, preferably, effected by means of a spring secured to 25 the liner and engaging one side of the slot, preferably the side which is provided with the usual grooves opening on the edge of the slot.

On casting the slug the liner will be secured 30 to the slug by the casting metal entering a recess provided in the liner, simultaneously as the metal enters the grooves on the side of the slot, thereby preventing displacement of the slug.

Our new tool comprises a graduated bar and a member slidably thereon and having a portion to 35 be brought into engagement with the liner, e. g. the recess thereof and abutting surfaces to be brought into engagement with the mold and a stationary end forming means or liner.

Our invention will be more fully described with 40 reference to the accompanying drawing in which connection also other features characterizing our invention will be set forth.

In the drawing:—

Fig. 1 is a front view of a mold having our 45 new movable liner inserted into the mold slot.

Fig. 2 is a top view of the mold with the cap removed and with a tool shown by dash and dotted lines for the adjustment of the movable liner.

Figs. 3, 4, and 5 are a top plan view, a side end view and a front end view, respectively, of the movable liner.

Fig. 6 shows the movable liner connected with 55 part of a slug.

Figs. 7, 8, and 9 are a top plan view and end views, respectively, of the adjusting tool.

The movable liner consists of a metal plate 1 and a spring 2 connected to the plate 1, said spring 2 being somewhat curved in direction from the plate surface so that the central part of the spring rests against one side wall of the mold slot 3. The thickness of the plate 1 is fitted to the width of the slot 3 of the mold 4, so that the plate 1 can readily slide in the said slot but, owing to the pressure of the spring 2 against the wall of the slot, is prevented from unintended displacement. The plate 1 is provided with a recess 5 extending over the whole width of the liner and limited at one side by the thicker head portion 10 of the plate and at the other side by flanged portions 6 of the plate. The cast type metal fills out the slot 5 so that the slug 7 (Fig. 6) to the left of the movable liner (Fig. 1) rigidly engages said liner but may be readily removed from same 15 at the removal of the liner from the mold. The usual grooves 8 in one side wall of the mold slot are filled by the cast metal of the slug 7 so that corresponding ribs 9 are formed on the slug which ribs by engagement in the grooves 8 hold 20 the slug and the movable liner in position. The width of the recess 5 in the movable liner is greater than the distance between two consecutive grooves 8 so that in every position of the liner the recess embraces at least one groove 8 25 in the side wall of the mold slot, causing the movable liner to be firmly secured in position after the metal has solidified in the recess 5.

The movable liner 1 is inserted into the mold slot 3 from the front side of the mold and is thereafter moved to a position corresponding to the desired length of the line. This lateral displacement may, of course, be performed in any suitable manner, but, preferably, the tool illustrated in Figs. 7 to 9 may be used for this purpose. This tool consists of a graduated bar 10 and a member 11 slidably mounted thereon. The sliding member 11 is provided with a latch 12 which by the action of a spring is maintained in engagement with tooth spaces 13 on the edge of the bar 10. The adjusted position of the sliding member 11 is indicated by a pointer 14 co-operating with the scale on the bar. The sliding member is also provided with a tongue 15 adapted to engage the recess 5 of the movable liner 1. 40 At its one end (the right one in the drawing) the bar is provided with a projection 16 having an abutting edge 17 at its end and a shoulder 18 on its rear side, said shoulder being in alignment 45 with an abutting edge 19 on the sliding member 50 55

11. The graduation on the bar 10 may indicate the length of the line in known units and is dimensioned with respect to the usual shrinkage of the type metal so as to obtain the proper length of the cast and cooled line.

5 For adjusting the desired length of the line the movable liner is inserted into the mold slot 3, as shown in Fig. 1. After adjusting the slidable member of the tool (according to Fig. 7 on 14 known units) the tongue 15 of the tool is put into the recess 5 of the movable liner 1. The abutting edge 19 of the slidable member 11 and the shoulder 18 on the projection 16 are brought into engagement with the front face 20 of the 10 mold and the tool is moved to the right until the abutting edge 17 engages the fixed end forming means or liner 21 at the right end of the mold slot.

15 During the casting of the slug the movable liner is secured in the slot by the pressure of the spring 2 against the wall of the slot. A slug is formed to the left of the movable liner 1 (Fig. 1) between same and a fixed liner 22, said slug with its right end portion engaging the 20 movable liner 1 so as to secure same in position during the subsequent casting of the type lines.

25 What we claim is:—

1. The combination with a mold having a slot 30 with opposed sides and spaced grooves on one side opening on the edge of the slot, of a movable liner having a spring secured thereto adapted frictionally to engage one side of the slot so as to maintain the liner in engagement between the 35 opposed sides of the slot, said liner being reciprocable in the longitudinal direction of the slot and having a recess adapted to be filled out with type metal to be rigidly connected to the slug at the side of the liner, said recess having a width

greater than the distance between two consecutive grooves.

2. The combination with a mold having a slot with opposed sides and grooves on one side opening on the edge of the slot, of a movable liner 5 reciprocable in the longitudinal direction of the slot and having a transverse head portion, a transverse flange having an opening and a recess between said head portion and said flange, said recess being adapted to be filled out with type 10 metal to be rigidly connected to the slug outside said flange, and a spring secured to said head portion adapted frictionally to engage the grooved side of said slot so as to maintain the liner in 15 engagement between the opposed sides of the slot.

3. A movable liner for the mold of a type slug casting machine adapted to be adjusted by means of a tool, there being an open slot between the 20 sides of said mold when the latter is in assembled condition, said liner comprising a plate inserted through said slot between the sides of said mold and movable therebetween longitudinally with respect to said slot to determine the length of a cast line, and being provided with a recess portion upon said plate opening in the same direction as the open front of said slot and adapted 25 to cooperate with and be engaged by said tool whereby to effect movement of said plate to a desired position longitudinally of said slot, while 30 said mold remains in assembled condition.

4. A liner for a type slug casting mold according to claim 3, wherein molten metal from a cast slug extends into the recess portion upon removal 35 of the tool, and upon congealing is rigidly unitary and integral with the metal of said slug.
